UNITED STATES PATENT OFFICE.

JOHN F. WOLLENSAK, OF CHICAGO, ILLINOIS.

DESIGN FOR A RAILING-BRACKET.

SPECIFICATION forming part of Design No. 17,395, dated June 14, 1887.

Application filed May 9, 1887. Serial No. 237,655. Term of patent 14 years.

To all whom it may concern:

Be it known that I, JOHN F. WOLLENSAK, a citizen of the United States, residing at Chicago, Illinois, have invented and produced a new and original Design for Railing-Brackets, of which the following is a specification.

My design relates to brackets to sustain railings along stairs, around areas, in cars, and any other places where hand, foot, or other railings are used, and which require brackets for their support.

In shape and appearance my design is intended to represent the grotesque figure of a fish, with the upper part of its body bent backward into the general outlines of a bird's neck, with a comb along its back, terminating in a head with a bird's beak, and surmounted by a ring, and with wings somewhat resembling those of a dragon. The whole figure is intended to be supported at substantially right

angles to the bracket-plate by resting upon its tail and a support in front.

What I claim is—

1. The design for brackets herein shown, which consists in the grotesque representation of a fish or similar marine creature, terminating in a head furnished with a bird's beak, and surmounted with a railing-ring, substantially as described. 25

2. The design for brackets herein shown, 30 which consists in the grotesque representation of a fish or similar marine creature, provided with wings and terminating in a head furnished with a bird's beak, and surmounted with a railing-ring, substantially as described. 35

JOHN F. WOLLENSAK.
